UNITED STATES PATENT OFFICE.

FRANK H. MOONEY, OF CHICAGO, ILLINOIS.

REGISTERING-BANK.

1,084,161.

Specification of Letters Patent.

Patented Jan. 13, 1914.

Application filed January 10, 1913. Serial No. 741,318.

To all whom it may concern:

Be it known that I, FRANK H. MOONEY, a citizen of the United States, residing at Chicago, in the county of Cook and State 5 of Illinois, have invented certain new and useful Improvements in Registering-Banks; and I do declare the following to be a full, clear, and exact description of the invention, such as will enable others skilled in the art 10 to which it appertains to make and use the same.

This invention relates to registers, and more especially to boxes such as those employed as savings banks; and the object of 15 the same is to produce a bank of this character which is constructed in simulation of an ordinary mantle clock, save that the hands on the dial are utilized for registering cents and dollars respectively.

20 An important feature of the invention consists in the mechanism employed in this connection whereby the insertion of any coin less than fifty cents and the depression of the main lever, turns the main wheel for a 25 distance proportionate to the value of that coin and advances the register accordingly.

Details of construction will appear in the following specification and claims, and are shown in the accompanying drawings 30 wherein—

Figure 1 is a general perspective view of the entire registering bank. Fig. 2 is a central vertical longitudinal sectional view of the forward end of the same. Fig. 3 is 35 a vertical transverse sectional view, taken on the line 3—3 of Fig. 2. Figs. 4, 5, and 6 are details showing the construction of the coin switch and the actuator mechanism controlled by the insertion and depression 40 of certain coins, Fig. 4 showing the parts at rest, Fig. 5 illustrating their action when a nickel is inserted, and Fig. 6 illustrating their action when a dime is inserted. Fig. 7 is a vertical section through the same elements on the line 7—7 of Fig. 6, and Fig. 45 8 is a horizontal section on the line 8—8 thereof. Fig. 9 is a perspective detail of what will be called the follower. Fig. 10 is a detail of a fragment of the dial. Fig. 11 is a detail of a fragment of the dial.

50 In the drawings the casing is shown as composed of an upright rear plate 1, an upright front plate 2 having a large opening in it for a purpose to appear below whereby this plate is in effect a frame, and a body 55 plate 3 arched over the top to conform with

the shape of the upper ends of the other plates—all the plates having feet at their corners so that when these plates are secured edge to edge as shown the feet constitute legs 4 on which the entire casing is supported. The bottom 5 of the casing is secured within the other plate above the legs 4, and is provided with a large opening which is normally closed by a door 6 held locked in place under ordinary conditions but tripped at certain times as will be described. The registering mechanism described below is disposed within the forward end of this casing between two upright plates 7 and 8 rigidly connected with and spaced from each other in any suitable manner. The forward of these plates, 7, stands in rear of the front plate 2 of the casing and closes the opening therein, and said plate 7 carries a dial 9 over whose face move the 75 hands of the register—the dial and hands being protected by a glass disk or crystal 10 which is securely held to the front plate 2 by means of a rim or band 11. The rear-most of said upright plates, 8, has at its upper end an extension 12 which projects through a slot in the arched top of the main or body plate 3 and which, with the parts secured thereto and carried thereby, constitutes the coin chute. This element in the 80 present embodiment of my invention is provided with a pair of upright slots 13 through which project the arms of the main lever which is here shown as a bail or looped wire 14 having its ends connected with the casing at the rear of the latter in any suitable way as by a clamp 15, while its looped or bent center 16 stands in position above the dial and serves as a handle by which the main 85 lever is actuated.

90 The parts thus far described, excepting those which are located within the casing, are by preference neatly finished as in brass or other ornamental metal, with an appropriate dial and its figures and appropriate hands, and the general appearance is that of a mantle clock, excepting only that the handle end 16 of the main lever is visible as shown in the drawings. Even this might be hidden by a suitable ornament if the face plate 2 of the casing were made ornamental, but as the handle will be manipulated each time a coin is inserted I prefer to have it within ready reach of the operator.

100 The registering mechanism in the present 110

case includes the dial, the hands, and the gearing connecting them. The face of the dial 9 is inscribed with twelve numbers 19 like an ordinary clock face, and is marked around its periphery with one hundred marks 20 instead of sixty marks like a clock face. The hour hand 21 moves from XII to I when one dollar has been inserted, and therefore when it makes a complete revolution over the dial it will indicate that \$12 has been deposited in the bank. I may here say that at that time the door 6 at the bottom of the casing falls open and delivers the \$12 to the saver or user, but this detail forms no part of the present application. The minute hand 22 makes one revolution each time one hundred cents has been inserted. It follows that the hour hand is true to the numbers 19 on the dial face, but the minute hand when turned by the insertion of twenty-five cents or a quarter of a dollar has moved to indicate a quarter of an hour and stands over III, though in this position it designates fifteen minutes and is not accurate with respect to the twenty-five cents. It follows also that the gearing between the two hands must be in the ratio of one to twelve the same as between the hands of a clock. On the shaft of the minute hand is a small pinion 23 meshing with a gear 24 whose hub 25 is toothed so that it constitutes a small pinion meshing with a gear 26 which is fast on the tubular shaft of the hour hand, and the teeth in the various gears and pinions are such that one complete revolution of the minute hand shaft causes the shaft of the hour hand to turn through one-twelfth of a revolution to carry out the object described above.

If it were the intention that the user of this bank should deposit nothing but coins of a single value and therefore of a single size, each time he inserted a coin and depressed the main lever the actuating mechanism would turn the shaft of the minute hand for a distance of one mark 20 if that coin were a cent or for a distance of five marks if that coin were a nickel, and so on; but in the present invention provision is made for the deposit of various coins up to and including a quarter, and the register-actuator must therefore be constructed accordingly.

Fast on the shaft of the minute hand is a main wheel 30 having one hundred teeth in its edge, and 31 is a retaining spring or pawl for preventing a retrograde movement of this wheel. The numeral 32 designates an actuating pawl, here shown as carried at the outer end of an arm 33 which is pivotally mounted on the shaft of the minute hand adjacent the main wheel, and said arm is provided with a longitudinal slot 34. The actuating lever is mounted on a main pivot 35 and has a depending finger 36 carrying at

its lower extremity a pin 37 moving in said slot 34 as best seen in Figs. 4 and 5, and in order that the movement of this finger shall swing the arm 33 to a proper extent it may be necessary to curve the slot 34 slightly as shown. The finger is forcibly moved in one direction by the insertion of a coin and its depression by the operator, and it is returned to its normal position as shown in Fig. 4 by a spring 39. The coin slot or run-way is in rear of the extension 12 at the upper edge of the plate 8, and is formed by securing a supplemental plate 42 behind said extension 12, as by soldering or brazing its flanged edges 43 to the edges of the extension, one of the flanges being cut away as at 44 to provide a coin-inlet. The plate 42 will be spaced from the extension 12 a distance equal to the thickness of the thickest coin the device is capable of handling, and it will have slots like those numbered 13 through which the arms of the main lever project as suggested above. The bottom of the coin chute is formed by a downwardly inclined switch plate 45 secured to the rear face of the extension 12 just beneath the inlet 44 as seen in Fig. 5, but this switch plate is of considerably less thickness than the distance between the extension 12 and the plate 42, and its upper edge is beveled as at 46 in Fig. 7. The disposition and proportion of parts is such that when a dime is inserted at the point 44, its lower edge slides over the bevel 46 and the entire coin falls past the switch plate 45; but when any other coin within the limits of this machine is inserted in the inlet 44, it travels down the upper edge of the switch plate 45 and beyond its inner end. As seen in Figs. 4, 5, and 6, the employment of such a switch plate delivers the coins to one or the other side of the main pivot 35 of the actuating lever, and the latter must therefore be constructed accordingly. For this purpose the upper end of said lever is forked, one arm 47 extending in a nearly vertical direction as seen in Fig. 4 and carrying a pin 48 moving in a slot 49 through the extension 12 and with reference to a fixed pin or stop 50; and all coins excepting the dime must be forced between these two pins before they can drop into the interior of the casing. The other arm 51 is longer than the arm 47 and extends obliquely from the pivotal point 35, and it carries a pin 52 moving in a slot 53 in the extension 12 with reference to a fixed pin or stop 54 at the inner end of the switch plate 45; and a dime which slips off the plate must be forced between these two pins 52 and 54 before it can drop into the interior of the casing. For depressing a coin in either position, a suitable follower 55 is provided, herein shown as consisting of a plate of proper thickness to fill the space between the 130

extension 12 and plate 42, and which follows the lower plate 55 is mounted on the arms of the main lever 14 and is therefore moved vertically when the handle 16 thereof is depressed.

With this construction of the actuator, its operation is as follows: Assuming that a nickel is inserted in the inlet when the parts stand as seen in Fig. 4, it travels down the switch plate and over and out of contact with the stop pin 54, its inertia will carry it over the pin 48, and it comes to rest against the stop pin 50. The operator then depresses the main lever, and the follower 55 pushes the nickel downward as seen in Fig. 5; this moves the pin 48 within the slot 49, and the arm 47 of the actuating lever is moved in one direction to cause its finger 36 to move in the opposite direction. The pin 37 at the lower end of said finger traveling in the slot 34, moves the arm 33 which carries the actuating pawl 32, and the tip of the latter engaging the teeth on the main wheel causes the rotation of such wheel and the movement 25 of the minute hand in a manner described above. As soon as the nickel has been forced through the space between the two pins 48 and 50, the spring 37 restores the parts to the position shown in Fig. 4. The same action would take place with a penny or a quarter, excepting that the actuating lever would be turned on its pivot 35 to a degree or for a distance corresponding with the diameter of these coins. When a thinner 35 and smaller coin representing a higher value is inserted, however, it would register too little if permitted to follow the same course. Therefore the insertion of a dime which has higher value than the larger nickel, must be made to turn the actuating lever to a greater degree. Entering the inlet 44, this coin slips off the plate 45 and drops into position between the pins 52 and 54 as seen in Fig. 6, and when the follower 55 is brought down by 40 the operator the pin 52 must be depressed for a considerable distance in its slot 53 before the dime can pass between it and the fixed pin or stop 54. This distance, added to the oblique disposition of the arm 51, causes the turning of the actuating lever to a greater extent, and the pin 37 at the lower end of its finger 36 therefore swings the pawl-carrying arm 33 through a larger arc and turns the minute hand on the register 50 to a greater extent. The parts will be properly proportioned so that any coin inserted, up to a quarter in the present illustration, will move the tip of the hour hand over as many marks 20 on the periphery of the dial 55 as that coin contains pennies.

It is quite obvious that this improved actuator mechanism could be employed with other forms of registering mechanism, or that the movement of the pawl-carrying arm 33 to a greater or lesser extent around its

pivotal point, which is the axis of the minute hand, could be made to perform other work than setting a register. Therefore I desire it understood that I do not wish to be confined to the use of this actuating mechanism 70 with this particular form of register, or in fact its connection with any register. The use of a relatively thin switch plate as a track at the bottom of a coin chute within a runway which is wide enough to admit 75 much thicker coins, may also be of advantage in other connections than herein illustrated and described, and with or without the illustrated form or any form of actuating mechanism and follower, and I reserve the right to the same accordingly. When \$12 has been deposited in this bank, the door 6 in its bottom is unlatched by mechanism forming no part of the present application, and which therefore need not be elaborated 80 in this specification.

What is claimed as new is:

1. The combination with a coin chute whose run way is composed of a switch plate at its inlet end narrower than the width of said chute, a stop pin across the inner end of said switch plate, and a second stop pin across the runway beyond the inner end of such plate; of a pivoted lever mounted on a main pivot beneath the plate 90 and having its upper end forked, one arm of the fork rising vertically from its pivot and coacting with one of said pins to admit coins of a certain size between them, and the other arm rising obliquely from said pivot 100 and coacting with the other of said pins, yielding means for holding this lever in position to prevent the admission of a coin without turning it on its pivot, a follower for forcing a coin between either stop and 105 its pin, and a register connected with said lever.

2. The combination with a coin chute having two fixed pins across its track, a vertically movable follower within said chute, 110 and means for depressing the same by hand; of an actuating lever mounted on a main pivot beneath the track and having its upper end forked, one arm of the fork rising vertically from its pivot and coacting with one of said pins to admit coins of a certain size between them, and the other arm rising obliquely from said pivot and coacting with the other of said pins, and yielding means 115 for holding this lever in position to prevent the admission of a coin without turning it on its pivot.

3. The combination with a coin chute having two stop pins across its track, a vertically movable follower within said chute, 120 and means for depressing the same by hand; of an actuating lever mounted on a main pivot beneath the track and having its upper end forked, one arm of the fork rising vertically from its pivot and coacting with 125

- one of said pins to produce a passage for coins of a certain size, and the other arm rising obliquely from said pivot and coacting with the other of said pins to produce another passage for coins of different size, a spring bearing against the lower end of said lever and turning it normally in a direction to contact said passages, and a register connected with this arm.
10. 4. The combination with a coin chute having two stop pins across its track, a follower within said chute, and means for moving the same toward said track by hand; of a pivoted actuating lever, two pins thereon at different distances from its pivot coacting with said stops to produce coin passages of different size, a spring turning the lever normally in a direction to contract said passages, registering mechanism including a ratchet wheel mounted on an axle, a retaining pawl for said wheel, an arm pivoted on said axle alongside the wheel and having an actuating pawl engaging its feet, its body being provided with a curved slot, and a pin in the lower arm of said lever loosely engaging said slot.
5. The combination with a coin chute having a stop pin across its track, a pivoted actuating lever having a pin in its upper end, means for pressing this pin normally toward said stop pin, and a follower for forcing said coin between said pins and turning the lever; of a spring tending to move the lever normally in a direction to contract the passage between said pins, registering mechanism including a ratchet wheel mounted on an axle, a retaining pawl for said wheel, an arm pivoted on said axle alongside the wheel and having an actuating pawl engaging its teeth, its body being provided with a curved slot, and a pin in the lower end of said lever loosely engaging said slot.
6. The combination with a coin chute whose run way is composed of a switch plate at its inlet end narrower than the width of said chute, a stop pin across the inner end of said switch plate, and a second stop pin across the run way beyond the inner end of such plate; of two other pins movably disposed with reference to said stops respectively, yielding means bearing each pin normally toward its stop, and a follower for forcing a coin between either pin and its stop.
7. The combination with a coin chute whose run way is composed of a switch plate at its inlet end narrower than the width of said chute, a stop pin across the inner end of said switch plate, and a second stop pin across the run way beyond the inner end of such plate; of a pivoted lever whose upper end is forked, pins carried by the arms of this fork, a spring moving said lever normally in a direction to bear said pins to-

ward their respective stops, a follower for forcing a coin between either stop and its pin, and a register connected with said lever.

8. The combination with a coin chute whose runway is composed of a switch plate at its inlet end narrower than the width of said chute, a stop pin across the inner end of said switch plate, and a second stop pin across the runway beyond the inner end of such plate; of a lever pivoted below said runway and carrying two pins at its upper end, the chute having a substantially horizontal slot within which the rearmost pin moves and a substantially upright slot within which the foremost pin moves and also having vertical slots above said runway, a follower within the chute above the runway, a yielding support for the follower projecting through said vertical slots, the rearmost pin coacting with the rearmost stop when thick and large coins are depressed by the follower and the other pin and stop coacting when thin and small coins are depressed, and a register actuated by the movements of said lever.

9. The combination with coin chute whose runway is composed of a switch plate at its inlet end narrower than the width of said chute, a stop pin across the inner end of said switch plate, and a second stop pin across the runway beyond the inner end of such plate; of a lever pivoted below said runway and carrying two pins at its upper end, the chute having a substantially horizontal slot within which the rearmost pin moves and a substantially upright slot within which the foremost pin moves, the rearmost pin coacting with the rearmost stop when thick and large coins are inserted, and the other pin and stop coacting when thin and small coins are inserted, means for moving said lever, and a register actuated by its movements.

10. The combination with a coin chute whose runway is composed of a switch plate at its inlet end narrower than the width of said chute, a stop pin across the inner end of said switch plate, and a second stop pin across the runway beyond the inner end of such plate; of a lever pivoted below said runway and carrying two pins at its upper end, the chute having a substantially horizontal slot within which the rearmost pin moves and a substantially upright slot within which the foremost pin moves, a follower within the chute above the runway, means for depressing said follower manually, the rearmost pin coacting with the rearmost stop when thick and large coins are depressed by the follower and the other pin and stop coacting when thin and small coins are depressed, a swinging arm connected with the lower end of said lever, a register, and pawl-and-ratchet mechanism between said arm and register.

11. The combination with a coin chute whose runway is composed of a switch plate at its inlet end narrower than the width of said chute, a stop pin across the inner end of 5 said switch plate, and a second stop pin across the runway beyond the inner end of such plate; of a lever pivoted below said runway and carrying two pins at its upper end, the chute having a substantially horizontal slot within which the rearmost pin moves and a substantially upright slot within which the foremost pin moves, a follower 10 within the chute above the runway, means for depressing said follower manually, the rearmost pin coacting with the rearmost stop when thick and large coins are depressed by the follower and the other pin and stop co- 15 acting when thin and small coins are depressed, a pivoted arm having a curved slot in its body, a pin in the lower end of said lever moving in said slot, a registering mechanism, and pawl-and-ratchet connections 20 between the moving end of said arm and such registering mechanism.
12. A coin chute having a runway whose bottom near its inlet end is formed of a switch plate thinner than the width of said chute, a stop pin across the inner end of said plate, a second stop pin across the chute remote from the inner end of the plate but in 25 line with its upper edge so that thicker and larger coins are dropped against the rear stop and thin and small coins are dropped past the plate and against the forward stop, movable pins coacting respectively with 30 such stops, and registering mechanism actuated by the movements of these pins when coins are forced between them and their respective stops.
- In testimony whereof I have hereunto set 35 my hand in presence of two subscribing witnesses.

FRANK H. MOONEY.
